[57] CLAIM

The ornamental design for a vacuum bottle, as shown
and described.

DESCRIPTION

FIG. 1 is a front, top and right side perspective view of
a vacuum bottle showing my new design, the vacuum
bottle being symmetrical about its axis;

FIG. 2 is a front elevational view thereof, the rear being
a mirror image thereof;

FIG. 3 is a bottom plan view thereof; and

FIG. 4 is a right side elevational view thereof.

FIG. 1

FIG. 2

FIG. 3

FIG. 4
